UNITED STATES PATENT OFFICE.

IWAN OSTROMISLENSKY, OF LOCUST POINT, NEW JERSEY, ASSIGNOR TO OSTRO PRODUCTS CORPORATION OF AMERICA, OF JERSEY CITY, NEW JERSEY, A CORPORATION OF NEW JERSEY.

MEDICAL PREPARATION CONTAINING ARSENIC AND PROCESS FOR MAKING THE SAME.

No Drawing

Application filed July 22, 1922. Serial No. 576,883.

This invention relates to improvements in medical preparations containing arsenic and processes for making the same. It relates more particularly to such preparations having the therapeutic properties of the salvarsan class, and processes for making the same. Salvarsan, as is well known, is dioxydiamino-arsinobenzol dichlorhydrate.

arsinobenzoic dichlorhydrate.

It is considered a postulate that every medical preparation and particularly medical preparations containing arsenic should be prescribed in minimal doses just sufficient to destroy the disease producing organisms in a patient's body while producing the desired therapeutic effect. Salvarsan and like materials are prescribed in doses which contain from 0.09 to 0.18 gram or more of arsenic. With doses such as these the patient is apt to become a "depot" of arsenic.

That is by the present methods of using salvarsan, for example in the treatment of syphilis, the gradual accumulation of arsenic in the treated person is inevitable. This accumulation leads to prolonged catarrhal conditions of the liver and hepatic ways and this catarrhal condition is apt to give rise to other more serious hepatic troubles in accordance with the findings of Prof. Dr. Arndt, Dr. Max Joseph and others.

The principal object of the present invention accordingly is to provide a series of medical preparations which shall not be apt to decompose upon standing and which shall

have the same or a greater therapeutic effect than salvarsan and similar materials in the treatment of diseases for which these substances are indicated, when prescribed in doses containing much smaller quantities of arsenic than present in the usual doses of salvarsan and the like. Another object of the invention is to provide a simple inexpensive process for obtaining such medicinal preparations.

preparations. The invention accordingly consists in a medicinal preparation which comprises an arsenic-oxygen compound, containing AsO_4 , $\text{As}(\text{OH})_2$ and its salts or the salts or anhydride of arsenious acid in solution with a protective colloid, such as gum-arabic, lysalbic acid, protalbic acid, gelatine, albumin, peptone, casein, human or animal blood serums and others. There may also be added to this preparation substances causing the solution to become isotonic with blood, if desired. Such isotonic substances include saccharine, glucose, Ringer's or Lock's solutions, sodium chloride and cane sugar.

In examining the hitherto unexplained process of the complicated transformations of salvarsan, neosalvarsan ("606," "914") etc. which, in themselves, occur at normal temperatures, without the presence of any catalizers or sensitizers or any other means of forcing the results, it has been discovered that a new reaction occurs, which can be expressed as follows: 60 65

It has also been observed that the known reaction of decomposition of the aromatic arsenious oxides (for example substance (1) in the above equation) by which are formed arsenious anhydride and the corresponding primary arsine, thus:—

can take place at normal temperature by itself under conditions approaching those found in a living body. It will be observed in accordance with the first equation that free arsenic is formed which as pointed out above inevitably accumulates in the patient's body. 85 90

The reactions above indicated require an appreciable time for completion. The first effect is that the colloid salvarsan or other injected substance is adsorbed in a selective process by the disease producing organisms, such as the spirochaeta of Obermeier, plasmodia Laverania, various tripanosomes etc. In this adsorption the reagents retain their original chemical properties. In 1911 Carl Lenhoff had shown that salvarsan is selec- 100

tively fixed by pallida spirochaeta of Schaudin on microscopic slides of various syphilitic materials. Bacteria and blood counts (Leucocytes, red corpuscles, etc.) of such slides remain unaffected. Salvarsan fixed by the spirochaeta retains for a long time its original chemical properties. For instance, it reduces almost instantly salts of silver and various other heavy metals. Also, if the above slide, after treatment with salvarsan, be submerged in a solution of silver nitrate, the spirochaeta are instantly colored black, which is the color of free silver. Spirochaeta which have not been treated with salvarsan do not reduce silver salts and therefore, naturally, do not become colored in a solution of silver nitrate (Lenhoff). The black color of colloidal silver appears with silver nitrate only on such portions of the slide as have adsorbed salvarsan in an unchanged form. Therefore we can observe directly with our own eyes the selective, purely physical union of salvarsan particles with the plasm of Schaudin's spirochaeta. This first and highly characteristic phase of mutual interaction between salvarsan (or other colloid) and the disease producing bacteria must without doubt be considered a physical process. The second phase consists of the decomposition of salvarsan as above described first, with the formation of the corresponding arsenious oxide and finally, the formation of the anhydride as well as of the corresponding salt of arsenious acid. These bactericidal products of auto-decomposition of salvarsan and its allied preparations form directly in the plasm of the parasites. When such products are sufficiently accumulated, they destroy the parasites. When a patient is treated with one of the preparations included in the present invention the colloid is selectively absorbed by the disease producing parasite to which the arsenious oxide anhydride or acid is simultaneously transferred. Thus the bactericidal matter is transferred instantly to the parasite plasm in a sufficient quantity to destroy the parasite. The following are examples of preparations which have been employed with excellent results, in accordance with the present invention, in the treatment of typhus recurrentis, syphilis, febris intermittens tertiana, sleeping sickness, carbuncles, framboesie, anthrax, nervous disorders and other diseases in which arsenic is applicable:

Examples.

1. 0.56 gms. of arsenious anhydride and 900 cc. of water are placed in a round bottom glass retort fitted with a return condenser. The mixture is heated over an open flame and allowed to boil for 40-60 minutes. A perfectly clear solution is obtained and to it is added a solution of 1.5 gms. of gum-

arabic in 100 cc. of water. To maintain the solution isotonic with blood, there is added to the general mixture 10 gms. of saccharose or 5 gms. of glucose, or 8.5 to 9 gms. of sodium chloride. Salts of Ringer's or Lock's solutions and others may also be used for the same purpose. The resultant solution is filtered, if necessary, and upon preliminary sterilization is distributed in phials.

The proper dose for treating syphilis, malaria or remittent typhus is 10-20 cc. This dose contains only 0.0042-0.0084 gms. of arsenic.

Example 2.—The curative solution is obtained identically as in Example 1, but the amount of gum-arabic added to the anhydride solution is reduced from 1.5 gms. to 0.45 gms., which also may be replaced by 0.45-1.5 gms. gelatine or by a mixture of 0.75 gms. of gum-arabic and 0.75 gms. of gelatine. The mixture is then treated as in Ex. 1.

Example 3. To a fresh solution of arsenious anhydride (1 gm.) and cane sugar (10 gms.) in 1000 cc. of water, are added, at normal temperature (15° C.), 3-6 cc. of human or horse blood serum. The solution must naturally be kept under sterile conditions. The curative dose of the preparation therapeutically equivalent to the normal doses of salvarsan (0.3-0.6 gms. for "606"; 0.45-0.90 gms. for "914" etc.) is at most equal to 10 cc., which contain only 0.0076 gms. of arsenic.

Example 4. 1 gm. of As_2O_3 , 2.6 gms. of gelatine and 10 gms. of cane sugar (or 8.5 gms. of NaCl) are dissolved simultaneously or consecutively, in any order, in 1000 cc. of pure water at boiling temperature. The curative dose of the resulting solution therapeutically equivalent to normal doses of salvarsan preparations contains only 0.003-0.006 gms. of arsenic.

Example 5. 0.5 gm. of paraoxyphenyl-arsenious oxide and 1-2 gms. of gelatine are dissolved simultaneously or in any consecutive order in 1000 cc. of water after the latter has been rendered alkaline by the addition of a very slight amount of sodium hydroxide. The proper dose of the resulting hypo-isotonic solution which is equivalent therapeutically to the normally prescribed dose of salvarsan preparations equals approximately 5 cc., which contain only 0.0025 gms. of arsenious oxide or 0.001 gm. of arsenic, according to the formula.

Example 6. The solution is prepared identically as in Ex. 5, but the gelatine is replaced by 1 or 2 gms. of gum-arabic or a mixture of 1 gm. of the latter and one gram of peptone, or a mixture of 0.5 gm. gelatine, 0.5 gm. gum-arabic and 1 cc. sterilized blood serum, etc.

Note: In order to render the solutions prepared according to Exs. 5 and 6 isotonic

with human blood, proper additions may be made of sodium chloride, salts of Ringer or Lock solutions, cane sugar, glucose or other equally effective substance. (German salvarsan" or Russian "navarsol")

Example 7. The preparation is identical with those obtained in Exs. 5 and 6, except that, instead of 0.5 gm. of paraoxyphenyl-arsenious oxide, 0.5-0.7 gm. of paraaminophenylarsenious oxide is used.

Example 8. A 10 gm. water solution of paraoxymetaminophenylarsenious oxide is added to 1000 cc. of an acidulated (by HCl) solution of 90 gms. of salvarsan in chemically pure, desiccated, and acetone-free, methyl alcohol. The combined solution is added to 9 liters of dry ether. A precipitate results, which is filtered, dried etc. is again dissolved for purification in pure methyl alcohol, free from acetone, and again precipitated by ether. Upon drying the second precipitate in a desiccator, a yellowish powder is obtained which contains practically the full 10% of the original arsenious oxide. The powder gives clear and fairly permanent solutions in water, without any residue, precipitate or turbidity. The correct dose of that preparation which is therapeutically equivalent to the normal doses (0.3-0.6 gm.) of German salvarsan equals on the average 0.075 gm. The dose is taken from a solution containing one gram of the powder resulting from the above procedure dissolved in 20 cc.-500 cc. of water.

It will be observed here that salvarsan is employed as a protective colloid replacing gum-arabic, gelatine, etc.

Example 9. A fairly strong current of air is passed in the dark through an acidulated (by HCl) solution of 100 gms. of salvarsan in 1000 cc. of moisture free, chemically pure, methyl alcohol. The process is continued for 6 hrs. To accelerate the reaction, fuming nitric acid of 1.4-1.5 specific gravity may be added up to 3 cc. to act as an oxidizing agent. At the end of the process the solution is poured into 10 liters of dry ether and the precipitate is filtered and further treated just as in the previous example.

Example 10. Alkaline solution of 100 gms. of German salvarsan in 10 liters of water is allowed to stand, open to air and at normal temperature, for 4-5 days. Then the solution is neutralized by very dilute hydrochloric acid. This results in the precipitation of dioxydiaminoarsenobenzol. The precipitate is separated by centrifuging, dissolved in hypochlorous acid in the presence of alcohol and precipitated by ethyl ether. After the precipitate is treated according to the usual procedure and is dried in a desiccator over paraffine and sulphuric acid, a yellow brownish powdery substance is obtained, which contains from 8 to 15% paraoxymetaminophenylarsenious oxide.

Example 11. A solution of 1 kilo of "914"

having the constitution

70

in 2 liters of distilled water is allowed to stand for 26 hours in an open vessel in the dark at normal temperature. The resulting product is then poured into 25 liters of 98% ethyl alcohol. A precipitate is formed which consists of the corresponding arsenous oxide

80

It is filtered, washed, pressed and dried to a constant weight, according to usual procedure. The resulting product contains from 8 to 15% of the corresponding arsenous oxide. The dose of the material so prepared is from 0.12 grams where 8% of the oxide is present to 0.06 grams where 15% of the oxide is present. The dose is administered preferably in water solution dissolved in 20-500 cc. of distilled water.

Neosalvarsan or Russian "navarsol" also acts here as a protective colloid.

Example 12. To 40 cc. of 0.1% solution of As_2O_3 prepared by boiling in a glass retort with a return condenser and cooled to normal temperature, is added a solution of 0.9 gms. of Russian neosalvarsan (i. e. "navarsol", containing 10% As) in 80 cc. of distilled water. The resulting product is arsenious acid physically bound, or adsorbed, by neosalvarsan as a protective colloid. The medical dose of this product which is therapeutically equivalent to normally prescribed quantities of neosalvarsan is approximately 10 cc. This quantity contains, therefore only 0.0075 gm. of As in the form of neosalvarsan and 0.0025 gm. of As in the form of adsorbed arsenious acid, or a total of 0.01 gm. of As as against 0.135 gm. of As which is usually given to patients in single injections of German neosalvarsan.

Example 13. A common solution of 5 gms. of arsenious anhydride, 2.5-3 gms. pure solid sodium hydroxide and 5-15 gms. gum-arabic (or an equal quantity of gelatine) in 125 cc. of water is added to 625 cc. of moisture free, chemically pure, methyl alcohol. To this mixture is gradually added, while stirring, about 200 cc. of dry sulphuric ether. A precipitate is formed which consists of sodium arsenite adsorbed by, or physically bound to, gum-arabic or gelatine or whatever other substance was used in their stead. The precipitate is filtered under pressure, washed carefully with dry ether, pressed out and finally dried in a desiccator to a con-

stant weight. It is recommended that once or twice during the drying of the final product it be pulverized into a fine powder by means of a porcelain pestle and mortar.

5 Example 14. Boil for one hour 1.2 gms. of arsenious anhydride with 100 cc. distilled water in a retort with a return condenser. Cool down the solution by water to 25° C. while shaking carefully. To 4 cc. of the 10 so obtained clear liquid add and dissolve by shaking 1.8 gms. of Russian neosalvarsan (navarsol), which usually contains only 10% of arsenic. After 5-10 minutes pour the 15 solution into 35 cc. of chemically pure moisture-free methyl alcohol. The precipitate which forms after the last operation is filtered under suction through a Buchner funnel, washed first with alcohol and then with ether, well pressed out and finally dried 20 in a desiccator over paraffine and sulphuric acid. No vacuum is required for the drying. The resulting product is a fine and, naturally, amorphous powder. The coloring is 25 of a not quite clear yellowish tint.

25 0.2 gm. of the above preparation, treated by Lemann's process, required, in a return titration of the separated free iodine, 14 cc. of 0.1 N solution of $\text{Na}_2\text{S}_2\text{O}_3$. Consequently, 30 the prepared substance contained arsenious anhydride and, possibly free arsenious acid, adsorbed by the neosalvarsan as a protective colloid. The preparation dissolves readily and completely in water giving permanent 35 perfectly clear solutions of a slightly yellow tint.

40 The peculiar physical condition of the mentioned organic arsenious oxides or the anhydride of arsenious acid etc. when adsorbed by colloids such as gum-arabic, gelatine neosalvarsan, Russian navarsol, salvarsan, "606", "914", is evidenced by a number of properties which they do not possess at all in their free chemically pure state. 45 Thus the substance—free, chemically pure, paraoxymetaminophenylarsenious oxide given in the last example, as is well-known, is not soluble in water, hydrochloric acid etc., while the arsenious oxide adsorbed by the salvarsan gives clear solutions in water. 50 When such solutions are accurately neutralized, or are treated with such reagents adapted to separate or precipitate dioxydiaminoarsenobenzol, or the acid or alkaline salts of the latter, this arsenious oxide is simultaneously also separated from the solution.

55 As a proof of the protective action of salvarsan it is also to be noted that pure paraoxymetaminophenylarsenious oxide is 20 times more toxic than salvarsan but when, as in the above example, this arsenious oxide is adsorbed by salvarsan the toxicity of salvarsan and combinations of salvarsan and this arsenious oxide have substantially equal 60 toxicity.

The preparations listed above, it will be understood, are simply examples of a large number of compositions employing the substances therein noted and similar substances falling within the scope of the invention. 70 Other arsenic-oxygen compounds and colloids than those set forth may be employed.

75 In general, by intravenous injection of paraoxymetaminophenylarsenious oxide physically bound with salvarsan as a protective colloid, a quantity of arsenic which is given the patient by a single injection of "606" or "914" can be reduced from 0.09-0.18 grams to 0.0045-0.0090 grams, and even less. With the use of the new 80 preparation neither the character of the treatment nor its intensity is changed and the usual medical effect is produced just as rapidly and is maintained for the same 85 length of time as when salvarsan alone is used without causing the patient to become a depot for arsenic.

90 Experiments have also shown in accordance with the invention that the same results as above are obtained by the use of neosalvarsan or Russian navarsol with its corresponding arsenious oxide.

95 In treating typhus recurrens, when using for intravenous injection a water solution of arsenious anhydride adsorbed by a small quantity of gum-arabic or gelatine, it is possible to reduce the quantity of arsenic required for obtaining terapium magnum sterilisans, almost 16 times, i. e. down to 100 0.056-0.0080 grams, instead of the 0.09-0.18 gms. usually applied in the form of salvarsan in such cases. After such injections of As_2O_3 , just as after the use of salvarsan, the attacks of typhus recurrens cease almost immediately, or at most in the 105 course of 3 to 12 hours and relapses do not occur at all.

110 Similar results have been obtained in accordance with the present invention in the treatment of malaric (febris intermittens tertiana) as well as of syphilis. In the case of the latter it has been observed that with a very small dose of arsenious anhydride in adsorption with gum-arabic, not only do the 115 external manifestations of syphilis show a rapid tendency to disappear but also as with salvarsan treatment, the patient's Wassermann reaction is changed from positive to negative.

120 Parallel clinical experiments in which arsenious acid was introduced as such without a protective colloid in one series of experiments and with a protective colloid as herein set forth in another series of experiments show that the characteristic medical properties of arsenious acid adsorbed by colloids are absent in the chemically pure reagent. On the contrary, intravenous injection of water solutions of chemically pure 125 arsenious anhydride in the same doses as 130

arsenious anhydride adsorbed by colloids sometimes causes sharp temperature reactions in the patient, but no appreciable therapeutic effect has been observed.

It will be observed that combinations such as those set forth in the examples may be made at ordinary or elevated temperatures.

Instead of the arsenious oxide compounds set forth in the examples phenyl arsenious oxide may be employed. Meta and ortho oxyphenylarsenious oxide may also be employed.

It will thus be seen that effective inexpensive simple medicinal preparations are provided in accordance with the invention adapted for use when arsenic compounds are indicated therapeutically, but which avoid accumulation of arsenic in the patient; and that simple processes for the manufacture of these preparations are also described. The term "organic arsenious oxide" as used herein refers to organic compounds containing the AsO group.

As many apparently widely different embodiments of the invention may be made without departing from the spirit thereof, it will be understood that I do not intend to limit myself to the specific embodiment herein set forth except as indicated in the appended claims.

Having thus described my invention, what I claim and desire to protect by Letters Patent is:

1. A composition useful for the treatment of syphilis, and diseases yielding to treatment by arsenic, comprising an organic arsenious oxide having by itself a high toxicity when present in the human body in the quantity of a dose and a protective colloid, said toxicity being reduced by said colloid to permit intravenous or other introduction into the body.

2. A composition useful for the treatment of syphilis, and diseases yielding to treatment by arsenic, comprising an organic arsenious oxide having by itself a high toxicity when present in the human body in the quantity of a dose, a protective colloid, said toxicity being reduced by said colloid to permit intravenous or other introduction into the body, and a substance isotonic with respect to blood.

3. A composition useful for the treatment of syphilis, and diseases yielding to treatment by arsenic, comprising an organic arsenious oxide having by itself a high toxicity when present in the human body in the quantity of a dose, gum-arabic, said toxicity being reduced by said gum-arabic to permit

intravenous or other introduction into the body, and glucose adapted to cause the compound to become isotonic with respect to blood.

4. A composition useful for the treatment of syphilis, and diseases yielding to treatment by arsenic, comprising paraoxyphenylarsenious oxide and a protective colloid, the toxicity of said paraoxyphenylarsenious oxide being reduced by said colloid to permit intravenous or other introduction into the body.

5. A composition useful for the treatment of syphilis, and diseases yielding to treatment by arsenic, consisting of an organic arsenious oxide having a greater toxicity in the quantity of a dose than a corresponding quantity of dioxydiaminoarsenobenzol dichlorhydrate, reduced to about the toxicity of said dioxydiaminoarsenobenzol dichlorhydrate by a protective colloid, and containing per equivalent dose a less quantity of arsenic than dioxydiaminoarsenobenzol dichlorhydrate.

6. A process for preparing a composition useful for the treatment of syphilis and diseases yielding to treatment by arsenic which comprises dissolving an organic arsenious oxide having by itself a high toxicity when present in the human body in the quantity of a dose and reducing the toxicity by combining therewith an organic protective colloid.

7. A process for preparing a composition useful for the treatment of syphilis and diseases yielding to treatment by arsenic which comprises dissolving an organic arsenious oxide having by itself a high toxicity when present in the human body in the quantity of a dose and reducing the toxicity by combining therewith a quantity of gum-arabic.

8. A composition useful in diseases yielding to treatment by arsenic, comprising an aromatic arsenious oxide and a protective colloid, the toxicity of said aromatic arsenious oxide being reduced by said colloid to permit intravenous or other introduction into the body.

9. A composition useful in disease yielding to treatment by arsenic, comprising an aromatic arsenious oxide containing a phenyl group and a protective colloid, the toxicity of said arsenious oxide containing the phenyl group being reduced by said colloid to permit intravenous or other introduction into the body.

Signed at New York, New York, this 21st day of July, 1922.

IWAN OSTROMISENSKY.
